UNITED STATES PATENT OFFICE.

WILLIAM P. BOVARD, OF MANSFIELD, OHIO, ASSIGNOR TO THE OHIO BRASS COMPANY,
OF MANSFIELD, OHIO, A CORPORATION OF OHIO.

DRILLING DEVICE.

1,341,292.

Specification of Letters Patent.

Patented May 25, 1920.

Application filed July 8, 1918. Serial No. 243,863.

To all whom it may concern:

Be it known that I, WILLIAM P. BOVARD, a citizen of the United States, residing at Mansfield, in the county of Richland and 5 State of Ohio, have invented certain new and useful Improvements in Drilling Devices, of which the following is a specification.

This invention relates to improvements in portable drilling devices and has for its 10 primary object the provision of means for rigidly securing the device to a rail, or any other suitable support to which it is desired to attach the mechanism.

Another object of the invention is to provide means of the character referred to 15 which will be durable and simple in construction, effective and efficient in operation, and which render the device capable of being readily and conveniently installed 20 or detached from its operative position.

A further object of the invention is to provide holding means for rigidly securing a drilling device to one side of a rail by engaging one or more surfaces thereof, and 25 which when secured in operative position will not form an obstruction in the path of or interfere with passing cars.

To the attainment of these ends and the accomplishment of other new and useful 30 objects, as will appear, the invention consists in the features of novelty in the construction, combination and arrangement of the several parts hereinafter more fully described and claimed and shown in the accompanying drawings illustrating the embodiment of the invention.

It is not the intention to cover herein the invention set forth and claimed in the applicant's co-pending application Serial 40 #137,164 filed Dec. 15, 1916, as the present application is an improvement thereon.

Figure 1 is a plan view of a portion of a rail and shows a drilling device positioned and secured thereto by holding means constructed in accordance with my invention.

Fig. 2 is a view looking at the bottom of the device or toward the drill bit (6).

Fig. 3 is a similar view as Fig. 1 and in 50 which the drilling device and the holding means are shown in cross-section in order to illustrate the constructional arrangement of the various parts.

Fig. 4 is an end view of a portion of a rail and shows a portion of the drilling device positioned thereto, and illustrates also,

the holding means (22) in position prior to being forced into engagement with the opposing surfaces of the rail for securing the drilling device to the rail.

Referring to the drawings and in which like reference characters indicate the same parts in the different views: (1) designates the body of a portable drilling device and which may be constructed as shown, the lower end comprising a lateral projection (2), provided with an aperture to receive the sleeve (3) which may be removably mounted therein by the nut (4). The sleeve (3) forms a guide and a bearing for one end of the spindle (5), the lower end of which has a drill (6), mounted therein in the usual manner, and its opposite end may be externally threaded for engagement with the internally threaded sleeve (7), mounted in the upper end of the body (1) and in alignment with the sleeve (3). It will be obvious from the foregoing and by referring to Fig. 3 that by rotating the sleeve (7), for which purpose the handle (8) may be provided, and holding the spindle (5) against rotation that by virtue of the threaded connection of the parts the drill may readily be moved into and out of engagement with the part to be perforated. In practice the drill is moved into engagement with the web of the rail or other part to be perforated by revolving the sleeve (7) in the manner above stated; the latter is then locked against further rotation as, for instance, by manipulating the hand wheel (9) in the direction to cause the spring (10) to exert pressure upon the plug (11), thereby to cause the end surface of the latter to yieldingly engage the sleeve and resist further rotation thereof. Rotary movement is then imparted to the spindle (5) by operating the lever (12) which may be provided and which, for convenience in operation may be equipped with a ratchet device (13) through which it engages the spindle.

The forward feeding movement of the spindle (5) may be further regulated by making the friction between (7) and (11) such that if the drill bit (6) is feeding too fast for the amount of cutting, then the increased pressure between parts (5) and (7) will be great enough to overcome the friction between the parts (7) and (11) and hence part (7) will for a period of time revolve with part (5), thereby automati-

cally stopping the forward feeding movement of spindle (5) and drill bit (6).

It will be obvious that by rotating the spindle (5) in one direction, by means of 5 its threaded connection with the sleeve (7), the cutting edges of the drill will be constantly urged into engagement with the part to be perforated and that by continued rotation thereof the drill will be forced to 10 cut its way through the object.

The above description briefly outlines a portable drilling device which is well known in the art and for which I make no claim other than in combination with my 15 improved holding and securing means and which I have selected for the purpose of illustrating the embodiment of the latter. It will be understood, however, that my invention is not limited to use with drilling 20 devices of this specific character but is equally adapted to be applied to drilling devices of other types and also with devices which are used for various other purposes.

In accordance with my invention the 25 lower end of the body (1) is formed with an extension (14) provided with rests (15) and (16), the end surfaces of which are disposed in a plane at right angles to the axis of the spindle and are adapted to seat 30 against the surface of the web of a rail or a support to which the device is to be secured. The extension (14) has an opening (17) passing therethrough to receive the stem (19) and which is inclined relatively 35 to the place in which the end surfaces of the rests (15) and (16) are disposed; the opening at the outer end of the extension is located at a greater distance from the longitudinal axis of the support than the opening 40 of its inner end.

Elongated slots (18) are formed in opposite sides of the extension (14) and in alignment with each other and communicate and are in line with the opening (17). 45 A stem (19) having a wedging member (20) mounted adjacent one end thereof by means of the set screw (21) is slidably received within the opening (17). The wedging member extends through the slots 18 wherein 50 it is longitudinally movable relatively to the opening (17), and has cutting edges (22) provided on its ends, the purpose of which will be described hereinafter.

When it is desired to secure the device to a 55 rail or the like it is positioned thereto as illustrated in Fig. 3 with the rests (15) and (16) bearing against the surface thereof. The stem (19) is then moved inward until the cutting edges (22) of the wedge come in 60 contact with the opposing surfaces (23), of the rail as shown in Fig. 4. Continued movement of the stem in the same direction by applying impact forces to the end (24) thereof, as for instance by striking it a blow 65 with a hammer, will cause the wedge member

(20) to move between the opposing surfaces (23) and toward the web of the rail, and by virtue of the relation of the parts the cutting edges (22) will be caused to penetrate the opposing surfaces of the rail. When thus positioned the device will be rigidly secured to the rail and for the purpose of preventing relative movement of the body member with respect to the stem (19), I provide a locking screw (25) which when adjusted to engage the stem interlocks the body member therewith. 70 75

The rest (15) acts as a thrust or pressure member when the device is being operated and the drill (6) is forced against the support. The thrust or pressure member (15) prevents the rotation of the device about the engaging point of the wedge (20) with the support, which acts as a pivot. This construction permits the use of only one securing wedge to attach the device to the support. 80 85

For the purpose of effecting the release of the wedge member (20), to permit the removal of the device, I provide a releasing 90 collar (26) which is preferably mounted in guides or slots (27), formed in opposite sides of the projection (2). These slots are formed by cutting away a portion of the sides at the lower end of the projection (2), and 95 likewise a corresponding portion at the upper end of the enlarged portion of the sleeve (3). Thus it will be noted that the releasing collar is retained in position by the sleeve (3), and may readily be inserted 100 into or removed from operative position. The collar (26) is formed with an elongated opening (28) which permits movement thereof to cause its end (29) to engage or disengage the end of the stem (19). 105

When it is desired to remove the device, the stem (19) is rendered movable by releasing the locking screw (25), then the releasing collar (26) is moved into engagement with the end of the stem and by applying impact forces to the end (30) of the latter, as by striking it a blow with a hammer, the wedge member (20) will be forced to disengage the opposing surfaces (23) of the rail and the device will be released therefrom. 110 115

Having fully described my invention and illustrated the embodiment of the same, I do not wish to be limited to the details of the construction shown since these can be obviously changed without departing from 120 the spirit and scope of the invention.

What I claim as new and desire to secure by Letters Patent is:

1. A drilling mechanism having a spindle for attachment to a support provided with 125 a slidably mounted means to engage the support and secure the mechanism thereto and means encircling the spindle and engaging the slidably mounted means to move the slidably mounted means out of engagement 130

with the support when impact blows are applied to the release means.

2. A holding device for attachment to a support provided with a flange or flanges comprising in combination a body member, a single one-piece-wedge-member slidably mounted in the body member to engage the support flange or flanges, mechanism provided on the frame to one side of the wedge-member and adapted, to engage the support and tending to turn the body member about the point of engagement of the wedge-member and support, and means positioned on the frame but on the opposite side of the wedge-member from that carrying the mechanism and which means opposes the rotation of the body.

3. A holding device for attachment to a support provided with a flange or flanges comprising in combination a body member, 20 a wedging means slidably mounted in the body member to engage the support flange or flanges, mechanism provided on the frame to one side of the wedging means and adapted to engage the support and tending to turn 25 the body member about the point of engagement of the wedging means and support, and means positioned on the frame but on the opposite side of the wedging means from that carrying the mechanism and which 30 means opposes the rotation of the body.

In testimony whereof I affix my signature.

WILLIAM P. BOVARD.
